UNITED STATES PATENT OFFICE.

HANS HAUPT, OF BERLIN, GERMANY.

COLLAPSIBLE UMBRELLA.

Application filed April 3, 1926, Serial No. 99,514, and in Germany July 2, 1925.

The present invention relates to an umbrella with telescopic sliding members. The novelty consists in this that a stick member which serves as the handle and is 5 slidable between the struts and the ribs is supported at both its ends when the stick is extended, by inner-lying stick parts, at the lower end by a firm connection with the lowest inner stick member, and at its upper 10 end by a piston-like guide capable of sliding in the handle tube.

By this double supporting of the handle tube any looseness of the handle is avoided and a smooth sliding in of the handle tube 15 between the struts and ribs without the same impinging on any projecting parts of the ribs, is possible.

Further, this double supporting of the handle tube assures that the guiding piston 20 sliding in the tube in spite of the large cross-section of the handle tube sliding over the struts, can be made very short so that the piston guide in its closed position only affects the length of the umbrella unessentially.

Moreover, according to the invention the umbrella stick is of such a kind that a middle member slides into the upper stick member and these and the slide to which the 30 struts are attached are capable of sliding together into the handle tube with the piston guide so that the handle tube lies between the struts and the ribs.

A constructional form of the umbrella is 35 shown by way of example in the accompanying drawing, in which

Figure 1 is a longitudinal section through the umbrella, only a single rib on one side being shown,

Figure 2 a longitudinal section through the inner parts of the stick to an enlarged 40 scale,

Figure 3 a longitudinal section through the umbrella frame also to an enlarged scale 45 with the parts slid together, some of the parts being in elevation,

Figure 4 shows the portion of a rib, to which the strut is pivoted, in longitudinal section,

Figure 5 the same part in plan view,

Figure 6 a diagrammatic cross-sectional view of the rib, to an enlarged scale, and

Figure 7 also to an enlarged scale, a longitudinal section through the ends of the two 55 parts of a rib, where they meet.

1, 2, 3 and 4 are the parts of the stick,

which are capable of sliding telescopically one in the other. The lower parts are embraced by a part 5 forming the umbrella handle, into which the upper parts 3 and 4 60 of the stick are capable of sliding with the aid of a guiding plunger 6 fixed to the part 3. 7 is a spring within the part 3 of the stick, the wall of which is at this place reinforced by an inner short piece of tube 8. 65 The spring serves the purpose both of locking the part 4 of the stick when extended and also of securing the sliding part 9, when the umbrella is open. The spring is released by hand when the umbrella is to 70 be closed, and, when the parts of the stick are slid together, by being pushed aside by the upper end of the part 1. Owing to the fact, that the outer tube 5 is guided on the third inner part 3 of the stick from the bottom, the lower parts 75 of the stick, 1, 2, 3 and 5 are secured by a single spring 11 which is fixed to the guiding member 6 and engages over the upper edge of the part 5 of the stick. The spring 80 11 must be released by hand. 12 is the crown of the umbrella. 13 and 14 are the two parts of the rib, which are capable of being slid together. 17 is a strut one end 85 of which is pivoted to the sliding part 9 and the other to the rib. On the parts of the stick being slid together the lower part 5 of the stick, as shown in Figure 3, is slid between the struts and the ribs into the upper 90 half of the umbrella frame or even close up to the upper pivotal joint of the strut 17, so that the ribs and struts are prevented from resting one against the other.

15 is a guiding sleeve fixed to the part 14 of the rib and 16 a guiding sleeve which is 95 fixed to the part 13 of the rib, but is capable of sliding on the upper part 14 of the rib. The strut 17 is not carried up as is usually the case, as far as the outer part 13 of the rib, but is pivoted to a member 18 on a sleeve 19 which is capable of being slid on the rib right up to the crown 12 of which, on the umbrella frame being extended, is secured by a projection 21 on the extension 20 of the part 18, which reaches between the parts 100 of the rib to the outer end of the part 14 becoming wedged between the sleeves 15 and 16 on the rib.

Notches or similar depressions are provided on the ribs, by which the parts of the 110 rib can engage with one another, when the latter is extended. Thus for instance the

- part 13 of the rib is provided with a shoulder 22, with which the said part of the rib rests against the sleeve 15, as long as it is not stretched out straight. For keeping the sleeve 15 pressed against the shoulder 22 a spring 23 is provided on the part 13 of the rib which spring embraces the sleeve 15. On the part 5 of the stick being slid over the strut 17 when the umbrella is pushed together (Fig. 3), the part 14 of the rib is drawn close against the umbrella stick, while the unsupported end of the rib provided with the ball point 24 is forced outwards over a thickened part 25 on the umbrella handle. Through the rib being forced out in this manner, the sleeve 15 is caused to leave the shoulder 22 thus enabling the parts of the rib to be pushed in at the same time as the part 5 of the stick.
- 26 is the umbrella cover which is fixed to the guiding sleeve 16 as well as to the ends of the ribs and confirms the fold 27, on the umbrella being pushed together. 28 is a loop for instance of leather provided on the end 29 of the stick. This loop is used as a handle for carrying the umbrella and also as something to get hold of when extending the umbrella frame.
- What I claim is:
1. A collapsible umbrella comprising in combination a stick, a plurality of ribs, both the stick and the ribs being in sections and capable of being slid together telescopically, a plurality of struts for supporting the ribs on the stick when the umbrella is open, and a hollow handle which extends when the umbrella is pushed together between the struts and the ribs, and a guiding member fixed on a section with the stick and capable of sliding within the hollow handle and of acting as a support at the upper end of the hollow handle for the sections of the stick within the hollow handle when the stick is extended, the lowest section of the stick being secured inside the handle to the bottom end of the said handle, as set forth.
2. A collapsible umbrella comprising in

combination a stick, a plurality of ribs, both the stick and the ribs being in sections and capable of being slid together telescopically, a plurality of struts for supporting the ribs on the stick when the umbrella is open, a slide to which the struts are attached, and a hollow handle which extends when the umbrella is pushed together between the struts and the ribs, and a guiding member fixed on a section with the stick and capable of sliding within the hollow handle and of acting as a support at the upper end of the hollow handle for the sections of the stick within the hollow handle when the stick is extended, the lowest section of the stick being secured inside the handle to the bottom end of the said handle, and the topmost section of the stick being capable of sliding over the section next below it and of sliding with it and the guiding piston and the said sliding tube to the struts into the hollow handle, as set forth.

3. A collapsible umbrella comprising in combination a stick, a plurality of ribs, both the stick and ribs being in sections and capable of being slid together telescopically, a plurality of struts for supporting the ribs on the stick when the umbrella is open, a 70 slideable member to which the upper end of the strut is pivotally attached and which is capable of sliding on the upper part of the upper section of the rib, guiding rings on the upper and lower sections of the rib for guiding them with respect to each other, an extension on the said slideable member, a projection on the said extension capable of becoming wedged between the two guiding rings on the rib sections by the rib being extended, and a hollow handle which extends, when the umbrella is pushed together, between the struts and the ribs into the upper half of the collapsed umbrella, as set forth.

In testimony whereof I have signed my name to this specification.

HANS HAUPT.
